UNITED STATES PATENT OFFICE.

WILLIAM PETRAUSKAS, OF BALTIMORE, MARYLAND, ASSIGNOR OF ONE-HALF TO
JOSEPH TARASEVICZIA, OF BALTIMORE, MARYLAND.

CREEPER-PLATE.

1,335,387.

Specification of Letters Patent. Patented Mar. 30, 1920.

Application filed August 2, 1919. Serial No. 314,962.

To all whom it may concern:

Be it known that I, WILLIAM PETRAUSKAS, a citizen of Russia, residing at Baltimore, State of Maryland, have invented certain 5 new and useful Improvements in Creeper-Plates, of which the following is a specification.

This invention has for its object the provision of means applicable to the heels of 10 shoes whereby the wearer is prevented from slipping upon icy or other treacherously slippery surfaces.

A further object is to provide such means in forms which may be readily attached or 15 detached from the heel of the shoe without disfiguring or damaging the same.

A still further object is to provide means whereby the spur elements of the creeper plates may be extended or retracted in an ex- 20 peditious manner so as to avoid damaging the spurs or defacing the surface trodden upon.

These and other like objects are attained by the novel construction and combination 25 of parts hereinafter described, and shown in the accompanying drawings, forming a material part of this disclosure, and in which—

Figure 1 is a side elevational view and 30 sectional view showing a fragment of a conventional type of shoe, parts being broken away and indicating the application of the invention, the section being taken on line 1—1 of Fig. 2.

Fig. 2 is a sectional view being taken substantially on line 2—2 of Fig. 1, and

Fig. 3 is a bottom plan view of the assembled device in detail.

Referring to the drawings in detail, the 40 numeral 10 designates the counter of a conventional type of shoe, merging into the instep portion 11, and the rigidly attached heel 12, engaged with the shoe as usual, the same being formed with a plurality of disks 45 or layers of leather or like material.

Surrounding the lower portion of the heel 12 is a casing comprised of an arcuate rear element 14, engaged by a pair of oppositely disposed hinges 15, with parallel side casings 16 and 17, similar in cross section to the rear element 14, the casing 16 having an angularly turned terminal 18, while the opposite casing has an angularly turned ele-

ment 19, shorter in length, while the element 18 extends past the center of the heel. 55

A pair of spurs 20 are formed by shearing and bending the material at the upper portion of the arcuate element 14, other spurs 21 extending inward from the side elements 16 and 17, these spurs entering into 60 the layers of the heel which rests upon inwardly extending flanges 22, 23 and 24 formed respectively with casing elements 14, 16 and 17.

A lug 25 extends centrally inward from 65 the flange 22 and pivoted thereon, by the rivet 26, is a lever 27, its free end containing an undercut recess 28, having a beveled front 29 engageable in the manner of a hook by a vertical latch 30, pivoted on an ex- 70 tension 31, formed in an inturned bottom projection from the element 18 at the center, the projection being further extended and turned vertically upward forming a lug 33 against which abuts a coiled compression 75 spring 34 by which the latch 30 is normally held in an engaging position, and carried by the latch 30 is a stem 35, provided with an actuating head 36.

A clip 37 held by rivets 38 to the inturned 80 casing elements 19, acts as a latch to hold the side elements 16 and 17 in close relation after they have been assembled upon the heel of the shoe.

A pair of rolled angular plates presenting 85 elements 38 and 39 carrying at their ends pins 40, are engaged in the side portions of the casing elements so as to rotate therein, the angular element 38 being provided with a plurality of sharp teeth 41, adapted to engage with the surface trodden upon, and are held in operative position by contact with the surface of the angular element 39 against the lever 27 when the same is disposed centrally of the casing whereby the spur carrying elements are prevented from turning. 95

In order however to allow the spur elements to be turned so that the spurs 41 are horizontal, the sharp angle formed at the intersection is removed, as at 42, so that when 100 the lever 27 is released from the latch 30 and turned to one side, as shown in the broken line in Fig. 2, the angular plates may be rotated upon the axis 40 into either position desired. 105

If it is desired to remove the creeper the

clip 37 is operated permitting the side elements 16 and 17 to turn upon the hinges 15, withdrawing the spurs 20 and 21 and permitting the device to be removed intact from the heel.

Having thus described my invention what I claim as new and desire to secure by Letters Patent, is—

1. In a creeper plate, the combination with an arcuate casing adapted to partially surround the heel of a shoe, side elements hingedly engaged therewith adapted to engage with the front of a heel, spurs formed interiorly of said elements engageable with the heel layers, a pair of angular elements pivoted between said side members, spurs on one of the edges of each angular element, and means for holding said spurred elements in an extended or retracted position.
2. In a creeper plate, the combination with a casing adapted to surround the heel of a shoe, and means formed therewith engageable with the material of the heel, of a lever pivoted in said casing below the heel at the rear thereof, means for engaging said lever at the front of the casing whereby it is held in a rigid position, a plurality of transversely disposed elements having angular

faces, and spur teeth formed upon the edges of one of said faces, said angular elements containing recesses permitting them to be rotated when said lever is moved into a certain position.

3. In a creeper plate, the combination with an arcuate metallic casing adapted to surround the rear portion of the heel of a shoe, angular elements engaged by hinges with said arcuate elements adapted to make contact with the front and sides of the heel, a lever pivoted at the center of said arcuate element and extending toward the front, means for locking said lever when in a central position, means for releasing said lever whereby it may be turned at an angle, a plurality of angle plates pivotally positioned between the sides of said casing in such manner that one of their faces makes contact with said lever, means formed with said angular plates permitting them to be rotated when said lever is in an angular position, and spurs formed upon one edge of each of said angle plates.

In testimony whereof I have affixed my signature.

WILLIAM PETRAUSKAS.
